(57) CLAIM

The ornamental design for an athletic sandal sole, as shown and described.

DESCRIPTION

FIG. 1 is a perspective view of one embodiment of the athletic sandal sole;

FIG. 2 is an anterior (front) view of the athletic sandal sole of FIG. 1;

FIG. 3 is a posterior (rear) view of the athletic sandal sole of FIG. 1;

FIG. 4 is a lateral view of the athletic sandal sole of FIG. 1;

FIG. 5 is a medial view of the athletic sandal sole of FIG. 1;

FIG. 6 is a top view of the athletic sandal sole of FIG. 1; and,

FIG. 7 is a bottom view of the athletic sandal sole of FIG. 1.

In FIGS. 1–6 the consistent length broken lines depict unclaimed environmental structure. The broken lines and the structures they depict form no part of the claimed design. The embodiment of the athletic sandal sole shown in FIGS. 1–7 is for a left foot. The embodiment of the athletic sandal sole for a right foot is a mirror image of the embodiment shown in FIGS. 1–7 about a sagittal plane of a human body.
